(57) CLAIM

The ornamental design for a bracket, as shown and described.

DESCRIPTION

FIG. 1 is a front view of the bracket showing my new design.

FIG. 2 is a back view thereof.

FIG. 3 is a side view thereof.

FIG. 4 is another side view thereof.

FIG. 5 is top view thereof.

FIG. 6 is a bottom view thereof.

FIG. 7 is a perspective view thereof; and,

FIG. 8 is a perspective exploded view thereof.

The broken lines in the drawings illustrate portions of the bracket which form no part of the claimed design.
